UNITED STATES PATENT OFFICE.

MONTGOMERY SLEETH, OF BELLEVUE, PENNSYLVANIA, ASSIGNOR TO FORT PITT BEDDING COMPANY, OF PITTSBURGH, PENNSYLVANIA, A CORPORATION OF PENNSYLVANIA.

SEPARATING DEVICE.

1,218,960.

Specification of Letters Patent. Patented Mar. 13, 1917.

Application filed November 3, 1915. Serial No. 59,479.

To all whom it may concern:

Be it known that I, MONTGOMERY SLEETH, a citizen of the United States, and a resident of Bellevue, in the county of Allegheny and 5 State of Pennsylvania, have invented a new and useful Improvement in Separating Devices; and I do hereby declare the following to be a full, clear, and exact description thereof.

10 My invention pertains to separating devices, and relates particularly to magnetic devices for separating extraneous metallic articles from cotton or the like. In the manufacture of mattresses, for instance, it 15 is customary to break up and mix the bulk cotton, or similar material, intended for filling the same. In such bulk cotton, there is commonly found a quantity of foreign metallic articles, such as nails, odd pieces of 20 iron and the like.

It is an object of the present invention to provide a simple and easily constructed magnetic device for abstracting such foreign articles. It is another object of the invention 25 to provide such a separating device with a simple means for effecting the final removal of the articles separated. And other and further objects of the invention will appear from the following specification 30 taken in connection with the claims appended thereto.

One form of separating device constructed in accordance with my invention is shown, by way of example, in the accompanying 35 drawing, and described in the following specification. It is to be understood, however, that the device may be embodied in other forms and that changes may be made in the embodiment shown and described, 40 without exceeding the scope of the invention, as defined in the appended claims.

In the drawing:

Figure 1 is a rear elevation of a separating device constructed in accordance with 45 my invention, showing the same as applied to a cotton breaking and mixing machine; and

Fig. 2 is a side elevation of the same, looking from the right hand side of Fig. 1, part 50 of the side wall of the breaking machine being broken away and the driving pulley omitted.

Like reference characters refer to like parts throughout the following specification

and the figures of the accompanying drawing.

The cotton breaking and mixing machine, to which the separating device is shown as applied, includes a frame having side walls 10 and 11, between which is mounted a rotating drum 12, over which passes a band 13, which latter is thus kept in continuous forwarding movement. The band 13 carries a plurality of pickers 14, which pick the cotton up in fragments from a supply hopper and carry it over to a delivery hopper, the effect being to break and mix up the cotton. Machines of substantially this character are well known in the art, and no further description of the same is, therefore, 70 necessary here.

Mounted on the inside of each of the side walls 10 and 11 is a standard 15, such standards being secured in place by means of bolts passing through clamping plates 17 75 on the outside of the side walls. These clamping plates are located at a position where recesses are cut in the side walls; so that no drilling or other tampering with the machine is necessary in attaching the standards.

The standards 15 are bent rearwardly at their top ends so as to terminate vertically above the axis of the drum 12. Between the standards is mounted a cross-bar 18, 85 which has hangers 19 pivoted thereto at its ends beyond the standards 15. The hangers 19 are connected together at their lower ends by means of a cross-bar 20, which carries a plurality of downwardly extending electromagnets 21, the cores of which pass through the cross-bar 20 and are secured thereto by means of nuts 22. As the cotton is carried over the drum 12 by the pickers 14, anything therein which may be formed 95 of iron or steel, and any iron or steel particles, are attracted by the magnets 21 and attach themselves thereto, remaining on the magnets, while the clean cotton proceeds to the delivery hopper.

In order that the separated articles attaching to the magnets 21, may be readily removed, the standards 15 are each provided with an end support 23, which supports carry between them a tray 24. Links 25 are 105 pivoted to the hangers 19, and slide in brackets 26 carried by the standards. The links are formed with notches 27 and 28,

one or the other of which notches engages the corresponding bracket 26, according as the hangers are in their operative position (Fig. 2 full lines), or in their inoperative position (Fig. 2, broken lines). When it is desired to remove the articles which have adhered to the magnets, the links 25 are lifted somewhat to clear their notches 27 from the brackets 26, and the hangers are then pulled upward, by means of the links, until the magnets 21 hang over the tray 24, in which position they are held by engagement of the notches 28 with the brackets 26. With the hangers in this position, current is shut off from the magnets, whereupon the articles dropped into the tray 24 which can be removed with them. In order that the vertical distances between the magnets 21 and the cotton passing thereunder may be varied to suit the requirements of any particular case, the hangers 19 are provided with a plurality of suspension holes for the links 25.

In order that both of the links 25 may be disengaged simultaneously, I provide a cross bar 31, the upwardly bent ends 30 of which are pivoted in brackets 27 carried by the standards 15. The points of the ends 30 engage beneath the links 25, so that, by rocking the cross bar 31, both links may be raised together, and their notches 28 disengaged from the brackets 26.

The device described above provides a very efficient means of removing iron and steel from cotton or the like. It is extremely simple of manufacture and can be produced at an exceptionally low cost. Furthermore its attachment to the machine requires no changes or alterations in the construction.

What I claim as new and desire to secure by Letters Patent is:—

1. The combination with a material-conveyer, of a pair of standards disposed, one at each side of said conveyer, a pair of hangers pivoted to said standards, a cross-bar carried by said hangers, electro-magnets car-

ried by said cross-bar, said hangers being disposed so as normally to support said cross-bar and magnets in proximity to said conveyer, a receiver carried between said standards, and means for moving said hangers to bring said electro-magnets into coöperative relation with said receiver. 50

2. The combination with a material conveyer, of a pair of standards disposed, one at each side of said conveyer, a pair of hangers pivoted to said standards and capable of vertical adjustment with respect thereto, a cross-bar carried by said hangers, electro-magnets carried by said cross-bar, said hangers being disposed so as normally to support said cross-bar and magnets in proximity to said conveyer, a receiver carried between said standards, and means for moving said hangers to bring said electro-magnets into coöperative relation with said receiver. 60

3. The combination with a material conveyer, of means for separating iron or steel articles from the material to be carried by said conveyer, said separating means including a pair of standards disposed one at each side of said conveyer, a pair of hangers pivoted to said standards and capable of vertical adjustment with respect thereto, a cross-bar carried by said hangers, electro-magnets carried by said cross-bar, said hangers being disposed so as normally to support said magnets in proximity to said conveyer, a receiver, means for removably mounting said receiver on said hangers, links carried by said hangers for moving the latter to bring said magnets into coöperative relation with said receiver, and means for retaining said links in the positions in which said electro-magnets are operative, and in which said electro-magnets are in coöperative relation with said receiver. 70 75 80

In testimony whereof, I the said MONTGOMERY SLEETH have hereunto set my hand. 90
MONTGOMERY SLEETH.
